UNITED STATES PATENT OFFICE.

ALFRED J. SWING, OF CINCINNATI, OHIO.

DESIGN FOR A TALKING-MACHINE CASING.

57,024.

Specification for Design.

Patented Jan. 25, 1921.

Application filed September 4, 1917. Serial No. 189,703. Term of patent 14 years.

To all whom it may concern:

Be it known that I, ALFRED J. SWING, a citizen of the United States of America, residing at Cincinnati, Hamilton county, State of Ohio, have invented a new, original, and ornamental Design for a Talking-Machine Casing, of which the following is a specification, reference being had to the accompanying drawings, forming a part thereof.

The outline and specific design or appearance of the wood casing of the talking machine is not an essential feature of my design. My design comprises the bell of the megaphone open and exposed to view and constituting a light reflecting and ornamental as well as useful element of the struc-

ture. This I attain by assembling a plurality of plane sections 4, meeting at their edges to form the flaring stationary bell or major megaphone section. By providing plane sections 4 which are strong reflectors of light, the light entering the bell is largely reflected therefrom and the effect of depth and darkness in the bell is avoided, and it is rendered light, pleasing and ornamental.

The sections 4 may be treated in any manner to attain a condition in which light is strongly reflected therefrom.

I claim:

The ornamental design for a talking machine casing as shown and described.

ALFRED J. SWING.
